WRINGER ROLL FOR CLOTHES WRINGERS

Filed Dec. 8, 1919

Patented Aug. 5, 1924.

1,503,953

UNITED STATES PATENT OFFICE.

GUSTAVE H. JANTZ, OF WYOMING, OHIO.

WRINGER ROLL FOR CLOTHES WRINGERS.

Application filed December 8, 1919. Serial No. 343,322.

To all whom it may concern:

Be it known that I, GUSTAVE H. JANTZ, a citizen of the United States, residing at Wyoming, in the county of Hamilton and State of Ohio, have invented certain new and useful Improvements in Wringer Rolls for Clothes Wringers, of which the following is a specification.

Wringer rolls as heretofore constructed comprise a central shaft to which has been affixed, in suitable manner, a cylindrical body of resilient material, such as rubber, the rubber having in practice been laid around the shaft in layers, and then vulcanized. Wringer rolls are usually provided with power transmitting means, for instance cog-wheels, at the respective ends thereof, and with driving means, for instance a hand-crank, when the wringer is intended for manual operation, or with a suitable cog-gear or cog-gears when the wringer is intended for power actuation, for instance in connection with a power washing machine.

The coating or covering of the wringer roll deteriorates in course of time, and when it has been desired to provide a new wringing surface, it has been found necessary for the user to purchase an entirely new roll, including the power imparting and the power transmitting means thereon, for the reason that, as heretofore constructed, the body of the resilient material or rubber has been permanently vulcanized to the shaft. Shafts of various lengths and with various propelling means thereon have heretofore been made by the different manufacturers of wringers, so that it has been necessary heretofore for the user, if he desired to renew his wringer roll, to obtain an entirely new roll and its attendant driving and transmitting means, from the manufacturer of the particular machine which he has been using.

It is the object of my invention to so construct the wringer roll that the resilient surface is provided with a foundation, so that the same may be renewed without the necessity of renewing the working parts connected therewith; further, to provide a driving shaft comprising a plurality of sections and having the power transmitting means thereon, and a wringer roll, provided with a resilient wringing surface, having releasable connection with said sections; further, to provide a wringer roll, com-

prising a shell having a resilient body thereon, and a driving shaft having releasable connection with said shell; and, further to provide a pluri-part shell, the parts of which are arranged to be connected and to receive the resilient body of the wringer-roll thereover, and a shaft releasably received in the shell, so that the shells with the resilient wringer-bodies thereon may be selectively placed upon and exchanged upon the shaft.

The invention consists in means for effecting these purposes, and in the novel construction, arrangements and combinations of the parts.

In the drawings:

Fig. 1 represents a front elevation of an exemplified wringer, embodying my invention, and adapted to be employed in connection with a power washing machine, parts being broken away and parts being shown in section for better illustration.

Fig. 2 is a similar view of one end of a wringer provided with manual operating means.

Fig. 3 is an enlarged axial section of a wringer roll embodying my invention, taken on a line corresponding to the line 3—3, of Fig. 5.

Fig. 4 is an axial section of the same taken on a line corresponding to the line 4—4 of Fig. 6.

Fig. 5 is a cross-section of the same taken on a line corresponding to the line 5—5 of Fig. 3.

Fig. 6 is a cross-section of the same taken on a line corresponding to the line 6—6 of Fig. 3; and,

Fig. 7 is a cross-section of the same taken on a line corresponding to the line 7—7 of Fig. 3.

The wringer frame is exemplified at 11, and may be of any suitable, usual or desired construction. A wringer roll 12 is arranged to cooperate with a wringer roll 13. The shaft of the wringer roll 12 is arranged to rotate in bearings 14 in the frame, and the shaft 15 of the wringer roll 13 is arranged to have bearings 16 coact therewith. The bearings 16 are arranged to slide in guideways 17 in the frame, pressure means being provided to exert pressure thereon for causing pressure between the rolls when wringing the clothes. A spring 18 may be employed to exert this pressure, being shown adjustable by means of a screw 19, threaded

in a bearing 20 on the cross-bar 21 of the frame. I have exemplified my invention as applied to the wringer-roll 12, which is the driving wringer roll of the pair, being, in practice, the lower wringer-roll.

Cog-gears 25 are fixed, as by pins 26, to the shaft of the driving wringer-roll and are arranged to mesh with cog-gears 27 secured fixedly, as by pins 28, to the shaft 10 of the driven wringer roll. Gear-covers 31 secured to the frame, may be provided for the cog-wheels and extend over the ends of the resilient portions of the wringer rolls for protecting the same and the clothes 15 which are being operated on.

The shaft of the driving wringer roll is provided with suitable driving means. These driving means may be either power driven or manually operated. I have in 20 Fig. 1 shown the same as power driven means, comprising a driving bevel-gear 36 which meshes with bevel-gears 37, 38, normally loose apart, to the shaft of the driving wringer roll, which is extended for the purpose. Collars 35, fixed by pins 39 to the shaft, hold the bevel-gears 37, 38, in mesh with the bevel-gear 36. A clutch-collar 40 has spline-connection 41 with said shaft and is arranged to be moved lengthwise into 25 neutral position, or for engagement of one of the clutches 42, 43, respectively for arrest positioning of the wringer-rolls, or for driving the wringer rolls in either direction.

I have in Fig. 2 exemplified the shaft of 30 the driving wringer roll provided with a crank-handle 46 of usual construction, secured to the shaft of the driving wringer-roll by usual means, as by a screw-threaded connection 47 between the hub of the crank-handle and said shaft, and a nut 48 received over the threaded reduced end 49 of said shaft.

It has been the practice heretofore, when 40 a wringer roll has become worn to replace the same with a new wringer-roll including the driving means thereon, as well as the cog-gears fixed thereto, for the reason that wringer rolls, as heretofore constructed, have been built up as integral structures including the central shaft, the resilient material vulcanized thereon, the cog-gears on the shaft, as well as the power driving means thereon, or the securing means thereon for the crank-handle when a crank-handle is 50 employed.

In my improved construction I mount the 60 resilient clothes contacting portion of the wringer roll on a releasable foundation so that this releasable foundation with its resilient covering may be replaced by a fresh or new releasable foundation with its resilient covering without the necessity of replacement of the shaft, the cog-gears or the driving means.

Exemplifying such construction I provide

a shell. This shell is preferably pluri-part, comprising the sections 51, 52. Each end of each shell-section has a section 53 of a bearing therein. The sections of the bearing at each end of the sleeve coact to form a positioning means for the shaft. The shell-sections are at a point intermediate of their ends provided with cooperating bearing sections 54, shown provided with sockets 55, the sockets of the respective bearing sections 75 coacting for receiving the ends of shaft-sections.

I prefer to provide a shaft comprising a plurality of shaft-sections, exemplified at 58, 59. The respective shaft-sections are 80 provided with the cog-gear 25 fixed thereto, one of the sections being also preferably provided with the driving means.

The respective shaft-sections are received into the shell through opposite ends of the latter, and the proximate ends of the shaft-sections are provided with parts which coact with the attaching means in the interior of the shell. The coacting parts of the shaft-sections are shown as ends 61, 62, received in the sockets, the walls of these ends coacting with the walls of the sockets for preventing relative rotation between the shaft-sections and the shell. The sockets, when the shell-sections are assembled, are exemplified as provided with flat sides, the ends of the shaft-sections being provided with coacting flat sides, so as to form a tongue and socket connection between the shaft-sections and the shell. 100

In order to provide for ready assembling of the parts, the respective shell-sections are provided with coacting shoulders 64, formed preferably by overlapping the peripheral wall of one of the shell-sections with the respective bearing-sections of the other shell-section, so as to cause correct and ready positioning between the shell-sections, for instance in lateral directions. Means are also provided for ready endwise positioning between the shell-sections, exemplified as a lug or lugs 66 on one of the intermediate bearing-sections received in a socket or sockets 67 on the other of the intermediate bearing-sections. The coacting lugs and sockets may be on any of the bearing-sections. The respective bearing-sections may be integral with the respective shell-sections.

Collars 71 are received over the ends of the shell-sections when the latter have been assembled. The collars act to press the shell-sections together. They may be secured to the shell-sections by suitable means, for instance a pin 72 received through apertures in the collar and the respective shell-sections. 120

The parts of the releasable wringer-roll thus far described, are preferably of metal, and form the foundation about which the resilient body 74, for instance rubber, is received. The shell, when connected, has 130

the rubber coating fixed thereto in any desired manner, as by providing the outer peripheral surface of the assembled shell between the collars with a binder coating, and arranging layers of rubber paste round about the latter, which rubber layers may comprise a body portion and an outer surface portion. The shell with its coating may then be placed in a suitable mold, and the resilient material vulcanized in usual manner, for fixing the cylindrical resilient body upon the shell. The collars serve as end walls for the rubber cylinder, the latter being however, preferably of greater diameter.

The shaft-sections may be assembled in the shell during assembling of the latter, or the shell may be secured to the shaft-sections after the releasable wringer roll is completed. When the latter manner of assembling is employed, the shaft-sections are inserted lengthwise into the respective ends of the assembled shell, the inner ends of the shaft-sections being placed in coactive relations with the inner bearing in the shell, for forming the driving relation between them, and preferably positioning the inner ends of the shaft-sections in all lateral directions in the shell. When this driving relation is effected, the portions of the shaft-sections which are in the outer bearings fill these bearings, so that the releasable wringer-roll is centrally located on the shaft-sections. The pins 72, which have been previously removed are again passed through the collars 71, the shell-sections, and the respective shaft-sections, for aiding in rotatively securing the shaft-sections and the releasable wringer roll together, and to prevent endwise movement between the shaft-sections and the releasable wringer roll. The coacting portions between the inner ends of the shaft-sections and the shell are such as to cause the axes of the shaft-sections and of the shell to be coincident.

When it is desired to renew the releasable wringer roll in my improved device, the pins 72 are removed, and the shaft-sections are withdrawn endwise out of the shell, a new releasable wringer-roll being substituted for the worn-out releasable wringer-roll, the shaft-sections and the new releasable wringer-roll, being re-assembled in the manner hereinbefore described.

In order to insure ready assembling of the parts, the inner end of the shaft-sections and the inner bearing of the shell are preferably provided with tapering ends, exemplified as the tapering ends 76 of the shaft-sections and the outwardly tapering ends 77 of the walls of the sockets, either or both of which may be employed. In order to facilitate the release between the shaft-sections and the shell I prefer that the reduced portions of the shaft-sections, or one

of the same, shall be sufficiently long to extend substantially through the length of the socket in the interior of the shell, for the purpose, if desired, that one of the shaft-sections may be employed to drive the other shaft-section endwise to release its connection in the inner socket and to provide for ready removal of the same.

I do not herein claim broadly the shaft comprising shaft-sections, so arranged that one of said shaft-sections is arranged to move the other endwise in its bearing means, or the intermediate bearing and recesses about the shaft-sections between the intermediate bearing and the end bearings herein shown and described, having shown, described and claimed the same in a copending application for Letters Patent of the United States on improvements in wringer rolls for clothes wringers, Serial No. 380, 85 777, filed May 12, 1920.

Having thus fully described my invention, what I claim as new and desire to secure by Letters Patent is:

1. In a wringer roll for a clothes wringer, the combination of a pluri-part shell, parted lengthwise of the axis of said shell to form a plurality of shell sectors, the respective parts of said pluri-part shell provided with complementary bearing-parts forming bearings at the ends of said shell, and with complementary bearing-parts intermediate of the ends of said shell, said complementary bearing-parts parted lengthwise of the axis of said shell to form a plurality of bearing-sectors, and a pluri-part shaft the respective parts whereof have bearing in said first-named bearings, and the inner ends of said respective parts forming releasable drive-connections with said last-named bearing-parts.

2. In a wringer roll for a clothes wringer, the combination of a shell comprising a plurality of shell-sections extending lengthwise of the shell, said shell-sections provided with shoulders limiting lateral displacement, said shell-sections provided with endwise positioning means, collars received about the ends of said shell-sections, and a resilient cover about said shell-sections between said collars.

3. In a wringer roll for a clothes wringer, the combination of a shell comprising a plurality of shell-sections forming substantial sectors of a cylinder extending lengthwise of the shell, shaft-sections, a resilient covering for said shell, the ends of said shell provided with bearings for said respective shaft-sections, the interiors of said respective shell-sections and the inner ends of said shaft-sections provided with coacting releasable driving connections within said resilient covering, and a cog-gear on each of said shaft-sections.

4. In a wringer roll for a clothes wringer,

the combination of a shell comprising a plurality of shell-sections extending lengthwise of the shell, the ends of said respective shell-sections provided with bearing-parts forming bearings at the respective ends of said shell, said respective shell-sections provided with locking bearing-parts intermediate of their ends, shaft-sections in said first-named bearings, the inner ends of said respective shaft-sections provided with locking-parts coacting with said locking bearing-parts, collars about the ends of said shell-sections for connecting said shell-sections, and positioning means between said collars, shell and shaft-sections, whereby to position the same axially of said wringer-roll.

5. In a wringer roll for a clothes wringer, the combination of a supporting shell and a pluri-part shaft, the respective sections 20 whereof extend inwardly from the ends of said shell to form proximate ends of said shaft-sections in said shell, the interior of said shell provided with inner bearing means in which said proximate inner ends of said shaft-sections are received, and driving connections within the interior of said shell between said inner ends of said shaft-sections and said inner bearing means to impart rotation from said inner ends of said shaft-sections to said bearing means.

6. In a wringer roll for a clothes wringer, the combination of a shell provided with a resilient covering, shaft-sections, said shaft-sections extending into the said shell from

the respective ends of said shell, the said shell having a bearing in its interior within said resilient covering for the inner ends of said shaft-sections, and driving connections between said shaft-sections and said last-named bearing to communicate motion from one of said shaft-sections to said wringer roll and the other of said shaft-sections.

7. In a wringer roll for a clothes wringer, the combination of a cylindrical shell provided with a cylindrical resilient covering vulcanized thereto, releasable shaft-sections received into the respective ends of said shell free from vulcanizing connection with both said shell and said cylindrical resilient covering, and means in the interior of said shell within said cylindrical resilient covering and spaced from the ends of said shell forming releasable drive connections between said respective shaft-sections and said shell, each of said shaft-sections having a journal at its outer end outside said shell for locating said respective journals outside the respective ends of said shell for coaction with the bearings of a wringer-frame.

In testimony whereof, I have hereunto signed my name in the presence of two subscribing witnesses.

GUSTAVE H. JANTZ.

Witnesses:
